UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

CRUSHING-MILL.

1,119,126.

Specification of Letters Patent.

Patented Dec. 1, 1914.

Application filed July 9, 1913. Serial No. 778,210.

To all whom it may concern:

Be it known that I, THOMAS J. STURTEVANT, a citizen of the United States, residing at Wellesley, in the county of Norfolk and State of Massachusetts, have invented or discovered certain new and useful Improvements in Crushing-Mills, of which the following is a specification, reference being had therein to the accompanying drawings.

This invention relates to that class of crushing mills employing rotary beaters or hammers which coöperate with grates or crushing surfaces in the chambers of the mills. In crushing mills of the class referred to most efficient operation is secured by such an adjustment of the beaters or hammers as will enable them to run closely adjacent to the grates or crushing surfaces. Owing, however, to the wear of the crushing parts, and more particularly to the wear on the rotary beaters or hammers, it is very desirable that a convenient radial adjustment of the working positions of the rotary beaters or hammers should be provided for, to compensate for wear, and the present invention has for its object to supply this desideratum.

In carrying the present invention into effect the rotary carrier preferably comprises a plurality of flanged collars splined to a rotary shaft, and attached to the flanges of these collars are disks having openings cut in such a manner as to provide internal gears. Fitting the said internal gears are toothed bushings or pinions in which are eccentrically mounted pivot-bars connecting the rotary beaters or hammers with the rotary carrier. Said toothed bushings or pinions are attached to said pivot-bars in any suitable manner, as by being pinned thereto. The toothed bushings or pinions at the ends of said pivot-bars mesh with a gear ring mounted on the outer collar on the rotary shaft, and said end bushings or pinions are notched or circumferentially grooved for the reception of a flange on a nut having a screw-threaded connection with said outer collar, so that by turning said nut the toothed bushings or pinions attached to the pivot-bars, and serving as eccentric supports for said bars, may be withdrawn from engagement with the gear openings in the disks. When thus disengaged from said

disks the connected pivot-bars and toothed bushings or pinions may be partially rotated for the purpose of varying the radial positions of the pivot bars and thus adjusting the radial positions of the rotary beaters or hammers pivoted thereon; and when such adjustment has been effected the flanged nut may be turned back to return the toothed bushings or pinions to their first position in engagement with the internal gear openings in the disks, and thus again lock said bushings or pinions against rotation.

In the accompanying drawing Figure 1 is a diametric section showing a rotary carrier and beaters or hammers pivotally mounted thereon in accordance with the present invention. Fig. 2 is an end view of the same looking from the left of Fig. 1. Fig. 3 is a detail view of one of the holding disks and Fig. 4 is a detail view of one of the toothed bushings or pinions to show the eccentric mounting of a pivot-bar.

Referring to the drawing, 12 denotes a rotary crushing mill shaft to which are splined a series of collars 13 and 14 provided with flanges 15. Riveted or otherwise suitably attached to the flanges 15 are disks 16 provided with openings 17 the walls of which are cut to form internal gears. The parts just described provide a rotary carrier for the rotary beaters or hammers 18 which are connected with said carrier by means of pivot-bars 19, on which are eccentrically mounted toothed bushings or pinions 20 and 21 fitting the internal gear openings 17 in the disks 16, and pinned or otherwise suitably secured to the said pivot-bars. Thus the said toothed bushings or pinions serve as eccentric supports for said pivot-bars. The outer bushings or pinions 20 have, integral therewith but separated therefrom, flanges 22 between which and the bodies of said bushings or pinions are notches or circumferential grooves 23 engaged by a flange 24 on a nut 25 threaded to the outer collar 13. By screwing the said nut to the left, Fig. 1, the toothed bushings or pinions 20 and 21 may be withdrawn from engagement with the rings 16, and when thus withdrawn the connected bushings or pinions and the pivot-bars 19 attached thereto may be partially rotated by

applying a wrench to squared portions 26 at the outer ends of said bushings or pinions. Preferably the outer eccentric toothed bushings or pinions 20 all mesh with a gear ring 29 rotatably mounted on the flange 16 of the outer collar 13, so that if a wrench be applied to the squared portion 26 of one of the outer bushings or pinions 20, to partially rotate the same, all of the other bushings or 10 pinions will be simultaneously rotated.

Owing to the fact that the pivot-bars 19 are eccentric to the bushings or pinions 20 and 21 partial rotation of these parts will effect a radial adjustment of the said pivot-bars and also of the hammers or beaters 18 pivoted thereon, and owing to the gear connections of the bushings 20, through the gear ring 29, the partial turning of one set of bushings or pinions 20 and 21 will effect 15 a simultaneous partial rotation of the other sets, to adjust all of the pivot-bars at the same time. When such adjustment has been effected the nut 25 may be screwed back to its first position, thus again bringing the 20 toothed bushings or pinions 20 and 21 into locking engagement with the disks 16. Accidental displacement of the nut 25, after it has been properly adjusted, will be prevented by a set-screw 27 provided with a 25 lock-nut 28.

From the foregoing it will be understood that the invention provides a convenient construction whereby the radial working positions of the rotary hammers or beaters 30 may be varied to compensate for wear and to bring them into any desired adjustment relative to the bars or crushing plates in the chamber of the mill.

The invention is not to be understood as 40 being limited to the exact details of construction herein shown and described, as such details may be varied without departing from the scope of the invention.

Having thus described my invention I 45 claim and desire to secure by Letters Patent:

1. In a crushing mill, the combination with a rotary carrier comprising disks, of 50 rotary beaters or hammers, pivot-bars connecting said beaters or hammers with said carrier, bushings in said disks in which said pivot-bars are eccentrically mounted, so that said bushings serve as eccentric supports for said bars, means whereby all of said bushings may be partially rotated simultaneously for the purpose of varying 55 the radial working positions of said beaters or hammers, and means for locking said bushings against rotation after adjustment.

2. In a crushing mill, the combination 60 with a rotary carrier comprising disks provided with internal gear openings, of rotary beaters or hammers, pivot-bars connecting said beaters or hammers with said carrier, toothed eccentric supports for said 65 pivot-bars and to which the latter are at-

tached, said toothed eccentric supports fitting said internal gear openings, means for withdrawing said toothed eccentric supports from said disks when desired, and means whereby said supports may be partially rotated to vary the radial working positions of said beaters or hammers. 70

3. In a crushing mill, the combination with a rotary carrier comprising disks having internal gear openings, of rotary beaters or hammers, pivot-bars connecting said beaters or hammers with said carrier, toothed bushings to which said pivot-bars are attached and in which said pivot-bars are eccentrically mounted, so that said bushings serve as eccentric supports for said bars, said bushings fitting said openings in said disks, a gear ring with which the outer set of said toothed bushings mesh, means for moving said bushings out of engagement with said disks, when desired, and means permitting partial rotation of said bushings when thus disengaged, for the purpose of varying the radial working positions of said beaters or hammers. 90

4. In a crushing mill, the combination with a rotary carrier comprising disks having internal gear openings, of rotary beaters or hammers, pivot-bars connecting said beaters or hammers with said carrier, toothed bushings to which said pivot-bars are attached and in which said pivot-bars are eccentrically mounted, so that said bushings serve as eccentric supports for said bars, said bushings fitting said openings in said disks, a gear ring with which the outer set of said toothed bushings mesh, a flanged nut having a threaded engagement with a part of said carrier and connected with said bushings so as to be adapted to move them 105 out of engagement with said disks, when desired, and means permitting partial rotation of said bushings when thus disengaged, for the purpose of varying the radial working positions of said beaters or 110 hammers.

5. In a crushing mill, the combination with a rotary carrier, of rotary beaters or hammers, pivot-bars connecting said beaters or hammers with said carrier, laterally 115 movable bushings in which said pivot-bars are eccentrically mounted, so that said bushings serve as eccentric supports for said bars, means for moving said bushings laterally, and means whereby said bushings may 120 be partially rotated for the purpose of varying the radial working positions of said beaters or hammers.

6. In a crushing mill, the combination with a rotary carrier, of rotary beaters or 125 hammers, pivot-bars connecting said beaters or hammers with said carrier, circularly adjustable and laterally movable eccentric supports for said pivot-bars, means whereby all of said eccentric supports may be par- 30

tially rotated simultaneously for the purpose of varying the radial working positions of said beaters or hammers, means for moving said bushings laterally, when desired, and means for locking said eccentric supports in working positions.

In testimony whereof I affix my signature, in presence of two witnesses.

THOMAS JOSEPH STURTEVANT.
